UNITED STATES PATENT OFFICE.

JOHN E. McCULLAY, OF PHILADELPHIA, PENNSYLVANIA.

IMPROVEMENT IN HOSE-BRIDGES.

Specification forming part of Letters Patent No. 136,745, dated March 11, 1873.

To all whom it may concern:

Be it known that I, JOHN E. McCULLAY, of Philadelphia, in the county of Philadelphia and State of Pennsylvania, have invented certain new and useful Improvements in Hose-Protectors; and I do hereby declare the following to be a full, clear, and exact description of the invention, such as will enable others skilled in the art to which it pertains to make and use it, reference being had to the accompanying drawing which forms part of this specification.

The drawing is a perspective representation of my invention.

My invention has for its object to provide means for protecting engine-hose from injury by cars and other vehicles. It consists in providing a bridge which, when a fire occurs, is erected in the street over the car-tracks, supporting the hose and permitting passing vehicles to go under it.

The bridge is designed to be portable, and for this purpose is generally made in sections, so that it can be packed in small compass and readily carried on the engine or truck.

Referring to the drawing, A A are sections of a bridge, consisting of uprights provided with projecting pointed feet. These uprights are provided with forked devices b at the top to form a rest for the hose and with braces a a. These braces may be made a part of the uprights, or rigidly attached thereto, or they may be jointed or so arranged that they can be extended according to emergency. The

braces meet at the point a' where the hose rests, a fork, b², being provided for that purpose. If desirable, the feet or ground braces d may be hinged on the upright, so as to be adapted readily to uneven surfaces.

This bridge is carried by the engine or truck. On arriving at a fire it is erected over the track and the hose placed in the forks before turning on the water. When raised the braces are brought together and locked, (or they may be locked before raising,) the hose resting in the forks; the water is then turned on. It may sometimes be necessary to raise the bridge after water has been already started, and a full hose will accordingly have to be raised. This may, of course, be done; but I prefer always to raise the empty hose, and after it has been brought into position to turn on the water.

What I claim is—

1. The hose-bridge, composed of the upright sections A and braces a holding the forked devices b b², substantially as and for the purpose specified.

2. The uprights A, having hinged or stationary feet or base supports, and provided with the hose-holders b, substantially as and for the purpose specified.

In testimony that I claim the foregoing I have hereunto set my hand.

JOHN E. McCULLAY.
